UNITED STATES PATENT OFFICE.

WILHELM KIMBEL, OF BERLIN, GERMANY.

WOODEN CIGARETTE CASE.

Application filed October 12, 1920. Serial No. 416,592.

To all whom it may concern:

Be it known that I, WILHELM KIMBEL, a citizen of the German Empire, residing at Berlin, Germany, have invented certain new and useful Improvements in Wooden Cigarette Cases (for which I have filed applications in Germany, March 19, 1919, Patent No. 325,659, September 15, 1920, and in England, July 6, 1920), of which the following is a specification.

My invention refers to cigarette cases and more especially to cigarette cases made entirely of wood and known generally as Russian cigarette cases. Up till now these cases were carved wholly by hand. The endeavours made up till now to produce such cases by machine, all failed without exception. Though it was possible to work the body and the lid of the case with machines, the attempts to manufacture the hinge connecting the lid and the body of the case with the aid of machines remained unsuccessful. The reason for these failures lay in the fact that the hinge parts of the body of the case as well as of the lid have cylindrical shape or form parts of a cylinder respectively, in order to make the hinge parts fit into one another tightly; consequently it is necessary to determine the curvature of the curved edges between the various tongues of the hinge by a circle the centre of which is located within the hinge-pin journal. Consequently the milling cutters must be extremely small, if machine manufacture is intended; in point of fact the diameter of the milling cutters must correspond approximately to that of the tongues of the hinge, which fact makes it perfectly obvious that such milling cutters cannot be employed. Even with the cigarette cases made by machine up till now it was therefore necessary to resort to manual labour, if only for working the hinges, this, however, increasing the costs of production so considerably that such cigarette cases proved a commercial failure.

My invention does away with the drawbacks mentioned by shaping the hinge in such a way as to allow of working the hinge by machine, whilst still maintaining a tight fit. The characteristic feature of my invention consists in the curved edges situated between the hinge tongues of the body of the case and of the lid forming part of a circle the centre of which is located outside the hinge-pin journal. Consequently it is per-

missible to employ larger milling cutters whose centres of rotation can have a position outside the section of the hinge pin and which can be therefore be employed satisfactorily for performing work on the hinge. In order to prevent the tobacco frequently dropping from cigarettes and collecting in the case from penetrating into the hinge even when the cigarette case is open (a regular occurrence with the cigarette cases as made hitherto) the bent edges existing between the hinge tongues of the body of the case, form the exterior surface of a wall or rib provided in the body of the case on the side fitted with the hinge, the said wall or rib protecting the hinge against the entrance of tobacco dust.

In the drawings affixed to this specification and forming part thereof a cigarette case embodying my invention, is illustrated by way of example. In the drawings.

Fig. 1 is a plan view.

Fig. 2 is an end view seen from the side fitted with the hinge.

Fig. 3 is a cross section of the case.

Fig. 4 is a longitudinal section of the case.

Fig. 5 is a section of the body proper of the case, and

Fig. 6 is a section of the lid proper.

Referring to the drawings, 1 is the body and 2 is the lid as usual. The body 1 as well as the lid 2 is provided with extensions 3 and 4 respectively which are delimited by two curved surfaces of varying radii, the holes 7 serving to receive the hinge-pin journal being arranged eccentrically in the said extensions. Moreover the curved edges 8 between the extensions 3 and 4 are determined by a circle the centre of which is situated outside the hinge-pin journal.

As will be noticed especially in Fig. 4 tight closing of the hinge is achieved in spite of the differing formation of the component parts of the hinge.

In order to prevent the tobacco dust which frequently collects in the body of the case from the cigarettes contained in it, from penetrating in between the component parts of the hinge, a wall or rib 9 is provided in the body 1 of the case on the side carrying the hinge, the said wall or rib being delimited by the curved edges 8 disposed between the single parts of the hinge. This rib prevents the tobacco dust from

slipping in between the component parts of the hinge, as will be observed in Figs. 4 and 5, the hinge therefore permanently remaining in good working condition.

5 Although I have described my invention as applied to wooden cigarette cases, it may obviously be applied with equal advantage to cases consisting of any other material of such as ebonite, celluloid, cellone, etc.

10 I claim:

1. In a device of the kind described in combination, a hollow body, a lid and a hinge integral with said body and said lid, the portions of the said hinge connected with said body being limited by a curved surface of a radius differing from that of the curved surface delimiting the portions of said hinge which are integral with said lid.

2. In a device of the kind described in 20 combination, a hollow body, a lid and hinges integral with said body and said lid, respectively, and cylindrical surfaces on said body and said lid intermediate said hinges, the hinge pivot being disposed eccentrically to said surfaces. 25

3. In a device of the kind described in combination, a hollow body, a lid and hinges integral with said body and said lid, respectively; cylindrical surfaces on said 30 body and said lid intermediate said hinges, the hinge pivot being disposed eccentrically to said surfaces, and a rib projecting into the interior of the body and adjoining said hinge. 35

In testimony whereof I affix my signature.

WILHELM KIMBEL
